(57) CLAIM

The ornamental design for a disposable diaper, as shown and described.

DESCRIPTION

The patent or application file contains at least one photograph executed in color. Copies of this patent or patent application publication with color photograph (s) will be provided by the Office upon request and payment of the necessary fee.

FIG. 1 is a front view of a disposable diaper, showing our new design;

FIG. 2 is a rear view thereof;

FIG. 3 is a top plan view thereof;

FIG. 4 is a bottom plan view thereof;

FIG. 5 is a right side view thereof; and,

FIG. 6 is a left side view thereof.

1 Claim, 5 Drawing Sheets
